DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

5 Sheets Drawing, 10 Pages Specification

Apparatus for and a method of cleaning a photoconductive surface wherein an open cell or partial open cell sponge material, such as polyurethane, is utilized for cleaning the photoconductive surface. The sponge material is either moved through a cleaning fluid or a cleaning fluid is adapted to flow through the sponge material during the cleaning operation. In one embodiment, the sponge material is wound in a helix on a core. In another embodiment the sponge material is ribbed radially and in a further embodiment the sponge material is ribbed longitudinally. In a still further embodiment the sponge material is an oscillatory pad and in another embodiment is in the form of a paddle wheel.
